E. H. Bond, Attorney

UNITED STATES PATENT OFFICE.

WILLIAM LINN, OF PHILADELPHIA, PENNSYLVANIA.

HANDEHOLD FOR CARS.

1,274,063.

Specification of Letters Patent. Patented July 30, 1918.

Application filed May 3, 1918. Serial No. 232,237.

To all whom it may concern:

Be it known that I, WILLIAM LINN, a citizen of the United States, residing at Philadelphia, in the county of Philadelphia and 5 State of Pennsylvania, have invented certain new and useful Improvements in Handholds for Cars, of which the following is a specification.

This invention relates to certain new and 10 useful improvements in hand holds for street or other cars and it has for its objects among others to provide a novel form of hand hold, with simple and effective means for checking or retarding the swinging of 15 the hanger strap. As is well known, the present form of hanging strap strikes the hat trimmings of ladies and the hats of men, and by reason of their construction and position cause the standing passengers to 20 press against those who are sitting, making it very unpleasant for ladies as well as for others.

The invention has for a further object the 25 provision of a novel form of hand hold which shall be sanitary and which can be readily wiped off when soiled and which, while hung high enough to allow headroom for the passengers in rising from their seats, shall be within comfortable reaching distance 30 for the standing passenger and which shall give each passenger an exclusive space, and providing a hand hold for as many passengers as can stand in the car.

The invention in its broad conception 35 embodies a hand hold made of one piece of expanded metal, extending substantially from end to end of the car and supported from the roof or from the side of the car by brackets or other means, with a chain or 40 the like within the expanded metal, and preferably with a rubber tube inclosing the chain or the like so as to prevent noise and allowing requisite elasticity, so that the same will bend sufficiently to prevent accidents and yet of sufficient strength to sustain a weight of say five-hundred pounds at 45 any point.

Other objects and advantages of the invention will hereinafter appear and the 50 novel features thereof will be particularly pointed out in the appended claims.

The invention is clearly illustrated in the accompanying drawings, which, with the numerals of reference marked thereon, form 55 a part of this specification, and in which—

Figure 1 is a vertical longitudinal section

of a portion of a car with parts broken away, showing the application of my present improvement.

Fig. 2 is a detail in vertical transverse section.

Fig. 3 is a detail in vertical transverse section, showing the hand hold supported from the side of the car.

Fig. 4 is an enlarged view, partly in side elevation, and partly in longitudinal section, showing a portion of the hand hold.

Like numerals of reference indicate like parts throughout the different views.

In carrying out my invention in its preferred form, I take a tube 1 of expanded steel or analogous material of a well-known spiral form, as seen best in Fig. 4, and within this I place a rubber tube or hose 2, preferably snugly fitting the same and through 75 this tube or hose I run a chain 3, the end links 4 extending through the rubber tube, as seen in Figs. 1 and 4, a sufficient distance to permit of the attachment thereof with hooks or the like 5 which are attached to 80 the end walls of the car in any suitable manner, as seen in Fig. 1.

The ends of the tube 1 are screw-threaded, as seen at 6, to receive caps 7, as seen in Figs. 1 and 4, the ends of the caps having 85 apertures 8 through which the end links 4 extend, as seen best in Fig. 4. The apertures 8 in the ends of the caps are only sufficiently large to admit of the passage of the links, the end portions of the caps serving as abutments for the ends of the rubber tube 2 so as to hold the same in position and prevent endwise displacement thereof, as will be readily seen upon reference to Fig. 4.

It will be understood that the metal 95 sheathing 1 is flexible so that the entire hand hold will bend in any direction in use.

The hand hold thus constructed may be supported in any suitable manner, as, for instance, by means of the hanging members 100 9, as seen in Figs. 1 and 2, or by the brackets 10 affixed to the side wall of the car in any suitable manner. Supported in either of the above ways, or in any other way, the hand hold will serve for as many passengers as 105 can stand up along the entire length of the car, each having his own respective place, and as the hand hold is flexible it will readily bend or yield as the car sways or as the passengers sway and all liability of accidents, as now happen with the present form 110 of straps where one-half of the standing

passengers have no support at all in a crowded car except by leaning on those near them and hence liable to be thrown against the windows or upon the other passengers, 5 is overcome.

The end caps may be readily removed for the purpose of repairs or whenever desired.

The sheath 1 may be coated with white enamel or some suitable material so as to 10 render the same sanitary and provide for the same being easily washed off should it become soiled.

Modifications in details may be resorted to without departing from the spirit of the 15 invention or sacrificing any of its advantages.

What is claimed as new is:—

1. A flexible hand hold for street cars or the like, embodying a sheath, a flexible member continued throughout the length of the hand hold with portions at each end thereof protruding through the ends of the sheath for holding the same supported longitudinally of the car.
- 25 2. A flexible hand hold for street cars or the like, embodying a spirally wound flexible sheath and a flexible member contained within the same with its end portions ex-

tended beyond each end of the sheath for supporting the hand hold in a horizontal direction at opposite ends of a car.

3. A flexible hand hold for street cars or the like, comprising a spirally wound metal sheath, a flexible tube within the same, and a flexible ligament within the tube with both 35 end portions extended.

4. A flexible hand hold for street cars or the like, comprising a spirally wound metal sheath, a flexible tube within the same, a flexible ligament within the tube with both 40 end portions extended, and caps on the ends of the sheath against which the ends of the flexible tube abut.

5. A flexible hand hold for street cars or the like extended horizontally and continuously 45 from end to end of the car with extended end portions, means for securing the ends of the hand hold, and intermediate supports for the hand hold.

In testimony whereof I affix my signature 50 in the presence of two witnesses.

WILLIAM LINN.
